UNITED STATES PATENT OFFICE

JOSEPH LEVY, OF BROOKLINE, MASSACHUSETTS

STAMP

Application filed September 29, 1930. Serial No. 485,092.

This invention relates to an improved hand stamp of the class in which a plurality of endless bands are provided upon their surface with characters such as numerals or letters. 5 These endless bands are supported at one end thereof upon a plurality of pulleys. At the other end they pass over a guide which in the present instance forms a cross-bar of the frame upon which the pulleys are mounted. 10 In order to position different numerals along the stamping line, or line of contact of the characters, with the surface which is to be printed, the bands are moved longitudinally thereof to different positions relatively to 15 each other. Heretofore this has been rendered very difficult by reason of the fact that when one band is moved the band adjacent thereto has been moved with it. In the hand stamp of this invention novel means 20 are provided to overcome this difficulty, consisting of flanges of different diameters which are provided on the band pulleys, so that one pulley can be rotated without rotating another pulley adjacent to it, and thus 25 each band may be efficiently and quickly positioned as may be desired, to present the desired character at the contacting line.

The invention consists primarily in providing the band pulleys of a hand stamp of 30 the character set forth with flanges of different diameters.

The invention further consists in certain details of construction as hereinafter described and pointed out in the claims.

Further, the invention consists in a stamp embodying the combination of elements set forth in the following specification and particularly pointed out in the claims.

Referring to the drawing:

Fig. 1 is a front elevation of the hand stamp of my invention.

Fig. 2 is a side elevation of the same.

Fig. 3 is a sectional elevation taken on line 3—3, Fig. 1.

Fig. 4 is a detail side elevation of one of the band pulleys.

Fig. 5 is a detail transverse section of the band guide.

Like numerals refer to like parts throughout the several views of the drawing.

In the drawing, 6 is a frame comprising a pair of side members 7 and 8 and a pair of cross bars 9 and 10. The side members 7 and 8 project into grooves 11 formed in the guide cross-bar 10 and are riveted thereto.

A pin 12 extends across the frame 6 and through the two side members 7 and 8 thereof and is fastened thereto. Upon this pin are mounted four pulleys 13, 14, 15 and 16. These four pulleys form a series of pulleys 55 adjacent to each other and are rotatably mounted upon the pin 12. The pulleys 13 and 16 form the terminal pulleys of the series and the pulleys 14 and 15 constitute the intermediate pulleys of the series. The pulleys 13, 14, 15 and 16 are provided respectively with flanges 17, 18, 19 and 20. The flanges 18 and 19 are of greater diameter than the flanges 17 and 20. A disc 21 is mounted upon the pin 12 between the pulleys 14 and 15. Endless bands 22, 23, 24 and 25 are mounted on the pulleys 13, 14, 15 and 16 respectively. These bands are provided respectively with a series of numerals 26, 27, 28 and 29, and the bands extend from the 60 pulleys around the band guide or cross-bar 10 which is provided with rounded corners 65 30. The cross-bar 10 is also provided in its lower edge with a recessed portion 33 which terminates at its opposite ends in shoulders 70 34, the width of the recess 33 being equal to the sum of the widths of the bands 22, 23, 24 and 25, thus guiding the bands and holding them close together adjacent the contact line 75 A—A, so that the numerals or characters on 80 the bands when printed on any surface will be positioned close together.

A detail front elevation of the pulley 16 is 85 illustrated in Fig. 4 as viewed from the left of Fig. 3, and it will be noted that the flange 90 20 of said pulley 16 is provided with corrugations 31 on its inner face or on the face adjacent to the pulley 16. The flange 17 of the pulley 13 is also corrugated in like manner 95 on the face adjacent to the pulley 13, while the flanges 18 and 19 respectively have the faces adjacent to the pulleys 14 and 15 corrugated. The object of these corrugations is to prevent the bands from slipping relatively to the pulleys when the pulleys are 100

rotated by means of their respective flanges. The pulleys 14 and 15 are separated one from another by the disc 21 which projects outwardly between the bands 27 and 28, so that 5 when these bands are adjusted one will not move the other by frictional contact therewith.

In order to operate the stamp conveniently, a handle 32 is provided which is fastened 10 to the cross bar 9 of the frame.

The operation of the device hereinbefore specifically described is as follows:—Assuming the different bands to be in the relative positions illustrated in the drawing and that 15 it is desired to position a different numeral or numerals upon the contacting line A—A, Fig. 2, if the numerals which it is intended to change is one of the numerals 26, then the pulley 13 is rotated by means of the flange 17 20 and as this pulley is one of the terminal pulleys and is positioned outside the pulley 14 adjacent thereto and has a flange 17 smaller in diameter than the flange 18 on the pulley 14, it follows that the pulley 13 can be easily 25 rotated without disturbing the pulley 14 until the desired numeral 26 is brought to the contact line A—A. If it is desired to bring one of the numerals in the series 27 to the contact line A—A, this is accomplished by 30 rotating the pulley 14 by means of the flange 18 and as the flange 18 is of greater diameter than the flange 17, said flange 17 will not be interfered with when the flange 18 is rotated by the fingers of the hand. The same is true 35 in relation to the setting of the band with the series 28 thereon, in which case the pulley 15 is rotated by means of the flange 19 and in the case of setting the numerals of the band 25 the pulley 16 is rotated by means of its flange 20. Thus any one of the pulleys may 40 be rotated and the band moved to bring any desired numeral or character which may be upon its surface into the contact line without interfering with the pulley and band or 45 bands adjacent thereto. The stamp is used in the usual manner, being manipulated by means of the handle 32, and in the present instance the bands and the characters thereon are preferably composed of rubber.

50 I claim:

1. A stamp having, in combination, a frame, a plurality of pulleys positioned adjacent to each other and rotatably mounted upon said frame, a flange upon each of said 55 pulleys, said flanges being of different diameters and corrugated on the face thereof from which its respective pulley projects, an endless band with characters thereon mounted on each of said pulleys respectively, and a guide for said bands parallel to and spaced apart from said pulleys.

60 2. A stamp having, in combination, a frame, a plurality of pulleys positioned adjacent to each other and rotatably mounted 65 upon said frame, a flange upon each of said

pulleys, said flanges being of different diameters, an endless band with characters thereon mounted on each of said pulleys respectively, and a guide for said bands parallel to and spaced apart from said pulleys, said guide having a single recessed portion therein through which all of said bands extend, the width of said recessed portion being equal to the sum of the widths of said bands. 70

3. A stamp having, in combination, a frame, a plurality of pulleys positioned adjacent to each other and rotatably mounted upon said frame, a flange upon each of said pulleys, said flanges being of different diameters, an endless band with characters thereon mounted on each of said pulleys respectively, and a guide for said bands parallel to and spaced apart from said pulleys, said guide having a recessed portion therein terminating at its opposite ends in shoulders, through which recessed portion said bands extend, the distance between said shoulders being equal to the sum of the widths of said bands, said shoulders holding said bands against lateral movement. 75

80 In testimony whereof I have hereunto set my hand.

JOSEPH LEVY.
